MATISON E. HINKLE, OF WINTERS, TEXAS.

SAW-GAGE.

1,297,689.

Specification of Letters Patent. Patented Mar. 18, 1919.

Application filed February 14, 1918. Serial No. 217,094.

To all whom it may concern:

Be it known that I, MATISON E. HINKLE, a citizen of the United States, residing at Winters, in the county of Runnels and State of Texas, have invented certain new and useful Improvements in Saw-Gages, of which the following is a specification.

This invention relates to saw gages, and more particularly to a device for gaging the depth of cut of a saw.

One of the main objects of the invention is to provide a device of the character stated of simple construction and operation which may be produced at relatively small cost and may be readily applied to a saw blade of standard construction. A further object is to provide a device by means of which the saw blade is gripped tightly so as to secure the gage in proper position thereon, the gage being provided with resilient gripping means so as to permit slight give of the saw blade when bent or flexed so as to prevent breakage thereof. A further object is to provide a gage having means for holding the blade of the saw in the gage in such a manner as to permit the gage to be readily adjusted on the blade before permanently securing the gage in position. Further objects will appear from the detailed description.

In the drawings:

Figure 1 is a side view of a gage constructed in accordance with my invention as applied.

Fig. 2 is a section taken substantially on line 2—2 of Fig. 1.

Fig. 3 is a section taken substantially on line 3—3 of Fig. 1.

The gage is provided with an inner U-clamp 1 and an outer U-clamp 2, as considered relative to the handle 3 of the saw 4 when the gage is in operative position. These clamps are formed by bending from resilient material of suitable gage, such as strap steel. Clamp 1 is provided with the integral downwardly directed arms 1^a and 1^b which are disposed in parallel spaced relation. Clamp 2 is provided with the integral parallel spaced arms 2^a and 2^b. As will be noted, clamp 1 is of greater height than clamp 2 so as to accommodate the inner or broader portion of the saw blade 4^a. A leaf spring 5 is fixedly secured at its upper end to the arm 1^a of clamp 1, adjacent the upper end thereof, by rivets 6. This spring is bent so as to extend transversely of the clamp, as

in Fig. 2. A gage strip 7 is secured to the lower end of spring 5 by a counter-sunk rivet 8. This strip is normally held pressed against the inner face of arm 1^b, adjacent the lower end thereof, by the spring 5. A clamping screw 9 is threaded through arm 1^a with its inner end bearing against the rivet 8, this screw being provided with a wing-head 10. Strip 7 is riveted adjacent its other end to a leaf spring 11 the upper end of which is riveted to arm 2^a of clamp 2 adjacent the upper end thereof, the strip being secured to this spring adjacent the lower end by the headed counter-sunk rivet 12. A clamping screw 13 is threaded through arm 2^a adjacent the lower end of the same, being provided with the wing-head 14, the inner face of this screw bearing against rivet 12.

As will be noted, the strip 7 extends below the arms 1^b and 2^b of the clamps 1 and 2, respectively. This strip is of such length as to extend substantially the full length of saw blade 4^a. In using this gage, the saw blade is first inserted into the clamps between the arms 1^b and 2^b and the strip 7. As the strip extends below the clamps, this is readily accomplished by forcing the strip inward away from the arms of the clamps and pushing the blade into the clamp. The springs 5 and 11 act to force the strip toward the arms 1^b and 2^b of the clamp so as to frictionally secure the saw blade between these arms and the strip. This permits the gage to be readily adjusted on the blade, while avoiding all looseness or play of the blade such as would interfere with proper adjustment of the gage. After the gage has been adjusted for the desired depth of cut, the clamping screws 10 and 14 are turned in so as to force the strip 7 into tight engagement with the blade, thus gripping the blade securely between the arms 1^b and 2^b of the clamps 1 and 2, respectively, and the strip 7. It will be understood, of course that the lower edge of strip 7 is adjusted parallel with the cutting edge 4^b of the saw blade and a distance away from the points of the teeth thereof corresponding to the depth of the cut desired. When thus adjusted, strip 7 serves as a gage which positively limits the depth to which the saw blade can enter into the material being operated upon. By this means, a saw of standard construction can be readily provided with means positively limiting the effective width of the blade, this means being readily adjustable so as to pro-

vide for cuts of different depths. As stated, the clamps 1 and 2 are formed from resilient material so that, while the saw blade is gripped securely it is not held absolutely rigid, a certain amount of flexing or bending being permitted, thus preventing breakage of the blade such as would be very apt to occur if an obstacle were encountered during the sawing operation, or the blade were to bind in the wood being sawed, and the blade were held absolutely rigid. It will be evident that there may be slight changes made in the construction and arrangement of the different parts of my invention without departing from the field and scope of the same, and I intend to include all such variations, as fall within the scope of the appended claim, in this application in which a preferred form only of my invention is disclosed.

What I claim is:
In saw gages, U-clamps adapted to fit

about the saw blade, leaf springs secured to one arm of each of said clamps adjacent the upper end thereof and extending transversely of the clamps, a gage strip secured to said spring adjacent the lower end thereof by rivets, said rivets being counter-sunk in the springs and having their outer end bent to provide bearing surfaces, and clamping screws threaded through the arms of the clamps to which the leaf springs are secured and engaging the outer end of said rivets so as to force the gage strip toward the other arm of the clamps for the purpose of frictionally gripping a saw between said strip and said other arm.

In testimony whereof I affix my signature in presence of two witnesses.

MATISON E. HINKLE.
